Attorney.

UNITED STATES PATENT OFFICE

2,095,636

GLIDER

William G. Hardy, Crafton, Pa., assignor to The McKay Company, Pittsburgh, Pa., a corporation of Pennsylvania

Application November 9, 1935, Serial No. 49,071

3 Claims. (Cl. 5—124)

My invention relates to gliders of the swing type, and has for one of its objects the provision of a glider structure which, while it may be formed of metal members which are of light 5 weight compared to the structures of previous gliders, is nevertheless of sufficient strength and rigidity.

Another object of my invention is to provide a glider structure which can be readily disassembled or knocked down, and which is of minimum overall length.

One form which my invention may take is shown in the accompanying drawings wherein Figure 1 is a face view of the glider; Fig. 2 is an end view thereof; Fig. 3 is an enlarged view taken on the line III—III of Fig. 2; Fig. 4 is an enlarged side view of a portion of the structure of Fig. 2; Fig. 5 is a view taken on the line V—V of Fig. 4; Fig. 6 is a view taken on the line VI—VI of Fig. 2, and Fig. 7 is an enlarged face view of a portion of the structure of Fig. 1.

The seat framework of the glider has at each end thereof, a yoke-like member 9 having an arm rest portion 10 and depending front and rear 15 leg-like portions 11 and 12, respectively. A rear seat bar 13 and a front seat bar 14 have welded thereto at each end a bar 15, the bars 13, 14, and 15 being preferably in the form of angles. Box springs 16 or other cushion-supporting elements 20 are supported by the angles 13, 14, and 15.

Brace bars 17 connect the leg elements 11 and 12 at each end of the seat structure, the ends of the bars 17 being laterally turned and welded to said leg elements. The use of these brace bars 35 permits the yoke members 9 to be made of lighter gage material than would otherwise be possible. The bars 17 also serve to prevent engagement of the cushions with the stationary end frames.

A back frame 18 has an angle bar 19 welded 40 to its lower end, the bar 19 extending the full length of the seat frame. A link member 21, at each end of the seat frame, has one of its ends pivotally connected to the back frame 18 and its other end pivotally connected to its associated 45 end bar 15. The bar 19 abuts against the rear sides of the links 21 and rearward tilting movement thereof is prevented, although it can be folded forwardly, when desired. The lower portions of the bars 21 seat against the upwardly-exposed faces of the bars 15. The pivotal connections of the links 21 are, of course, removable, in order to facilitate disassembling of the structure.

In order to provide for a firmer connection between the seat bars, I provide a yoke bar 23 at

each end of the seat frame. The bars 23 are welded to the leg members 11 and 12 and have their ends inwardly turned, such ends extending beneath the bars 15 and lying within the angles of the bars 13 and 14. The said inner ends carry 5 pins or buttons 24 that have interfitting engagement with key hole slots formed in the bars 13—14, as shown more clearly in Figs. 6 and 7.

The bars 15 and the pin and key hole connections referred to maintain the parts in rigid relationship. In order to overcome danger of accidental disconnection of the pins 24 from the key hole slots, the bar 23 may be slotted slightly to permit of tongues 24a being struck up therefrom, and bent to the position shown in Fig. 7, between 10 the ends of the bars 13 and 14 and the legs 12—11, respectively. However, by disengaging the key hole connections and disconnecting the links 21, the seat frame structure can readily be knocked down for shipment or storage.

The stationary portion of the structure includes a pair of end frames each having a floor bar 26 that may suitably be provided with rubber caps or pads 27; a pair of supporting bars 28 disposed in crossed relation, and a top rail 29. 25 Brace bars 31 are connected at each end to the uprights 28. These bars may suitably be of angular form and have the heads of bolts 32 welded therein, the bolts extending beyond the ends of the bars, and through the uprights 28. When 30 nuts are attached to the bolts, the end frames are thereby rigidly connected.

The lower ends of the crossed bars 28 are welded to the sides of the floor bars 26, and their upper ends are welded within the groove or channel 35 portions of the top rails 29, and may be welded at their points of crossing. One bar 28 of each pair is offset somewhat, as shown more clearly in Fig. 6, so that the ends of the uprights where they are connected to the floor bars 26 and to the top rails 29, will lie in a common plane in each instance.

The seat frame is supported upon stationary end frames, at its four corners, by strap-like members 34 which are here shown as of spring steel; although these hanger members could be in the form of links. However, I prefer to use the spring strap hangers, because they permit of a smoother and noiseless swinging movement and resist any thrusts which tend to produce end 50 sway of the seat.

The upper ends of the straps are connected to the down-turned flat portions of the top rails 29, by means of bolts 35. While the straps 34 will ordinarily flex at various points throughout 55

substantially their entire lengths during swinging movements, I find that any tendency toward localized bending at the vicinity of the bolts 35, particularly if the spring straps are of light gage, is reduced by employing short plates or strips 36 of spring steel, which are clamped against the faces of the strap by the bolts 35 and will flex somewhat.

5 The lower ends of the straps 34 are connected 10 to the leg portions 11 and 12 of the seat frame in substantially the same manner as the upper ends thereof are connected to the top rails 29, spring plates 37 being employed in the same manner as the spring plates 36.

15 It will be noted that the yoke members 9 of the seat frame are positioned over and lie in the same planes as the stationary end frames. In order to prevent interference by these yoke members with swinging movements of the seat frame, 20 the arm rest portions 10 are made of considerably greater length than the leg portions and therefore are inclined downwardly toward one another, for connection to the lower ends of the vertically-extending straps 34.

25 Since the seat bars are inclined relative to the yoke-like member 9 and the end frames, with a higher point of connection with the leg elements 11 than with the legs 12, and the yoke members 9 are of light gauge material, stiffening strips 39 30 are welded to the rear sides of the front legs 11.

I claim as my invention:—

1. A glider comprising a pair of stationary end frames each of which includes a top rail, a floor bar, a pair of substantially flat uprights disposed 35 in relatively crossed relation and secured at their upper and lower ends to the top rail and the floor bar, respectively, one of the uprights being offset

to cause their upper and lower ends to occupy a common vertical plane, suspending elements connected to the ends of the top rails, and seat-supporting legs connected to and extending upwardly from the lower ends of the suspending elements, the legs, the top rail and the uprights, 5 at each end of the glider, being disposed in a common vertical plane.

2. A glider comprising a pair of stationary end frames each of which includes a top rail of channel form and having down-turned ends, a floor bar, a pair of substantially flat uprights disposed in relatively crossed relation and secured at their upper and lower ends to the top rail and the floor bar, respectively, one of the uprights 10 being offset to cause their upper and lower ends to occupy a common vertical plane, suspending elements connected to the ends of the top rails, and seat-supporting legs connected to and extending upwardly from the lower ends of the suspending elements, the legs, the top rail and the uprights, 15 at each end of the glider, being disposed in a common vertical plane.

3. A glider comprising a pair of stationary end frames each of which includes a top rail, a 25 floor bar, a pair of uprights secured at their upper and lower ends to the top rail and the floor bar, respectively, suspending elements connected to the ends of the top rails, seat-supporting legs connected to and extending upwardly 30 from the lower ends of the suspending elements, in relatively flared directions, and an arm rest carried by the upper ends of the legs, the legs, the arm rest, the top rail and the uprights, at each end of the glider, being disposed in a common vertical plane.

WILLIAM G. HARDY.
